GARMENT HANGER

Sidney Simon, Philadelphia, Pa., assignor to Pyramid Products Corporation, Philadelphia,
Pa., a corporation of Pennsylvania

Application December 8, 1948, Serial No. 150,039

Term of patent 14 years

(Cl. D80—8)

To all whom it may concern:

Be it known that I, Sidney Simon, a citizen of the United States of America, residing in Philadelphia, county of Philadelphia, and State of Pennsylvania, have invented a new, original, and ornamental Design for a Garment Hanger, of which the following is a specification, reference being had to the accompanying drawing, forming a part thereof:

Fig. 1 is a perspective view of a garment hanger showing my new design with the hook in its raised position; and

Fig. 2 is a side elevation of a garment hanger shown in Fig. 1 with the hook folded.

I claim:

The ornamental design for a garment hanger, substantially as shown.

SIDNEY SIMON.
